DESIGN FOR A GOLF CLUB HEAD

Vincent K. Hilton, Dayton, Ohio

Application August 11, 1936, Serial No. 64,357

Term of patent 14 years

To all whom it may concern:

Be it known that I, Vincent K. Hilton, a citizen of the United States of America, residing at Dayton, in the county of Montgomery, State of Ohio, have invented a new, original, and ornamental Design for a Golf Club Head, of which the following is a specification, reference being had to the accompanying drawing, forming part thereof.

In the drawing,—

Fig. 1 is a perspective view of a golf club head embodying my new design;

Fig. 2 is a side elevational view thereof;

Fig. 3 is a sectional view thereof taken on the line 3—3 of Fig. 2; and

Fig. 4 is an end elevational view thereof.

The dominant features of the design consist in the perpendicular relationship of the adjacent sides of the club head accentuated by a band or strip at the opposite parallel sides thereof, as shown.

I claim:

The ornamental design for a golf club head, substantially as shown and described.

VINCENT K. HILTON.
